Attorney

UNITED STATES PATENT OFFICE

CHARLES A. BATCHELDER, OF ST. ALBANS, MAINE

SHOE TREE

Application filed February 19, 1932. Serial No. 594,095.

This invention relates to shoe trees and more particularly to a novel adjustable connection between the sections thereof.

A primary object of the invention is to provide a connecting device which is easy to make and assemble, and which when assembled will perform the dual function of connecting the two sections for adjustment purposes and also prevent the complete separation thereof.

With the above and other objects in view which will more readily appear as the nature of the invention is better understood, the same consists in the novel construction, combination and arrangement of parts herein-after more fully described, illustrated and claimed.

A preferred and practical embodiment of the invention is shown in the accompanying drawing, in which:—

Figure 1 is a plan view of the improvements embodying the invention.

Figure 2 is a longitudinal sectional view taken on the line 2—2 of Figure 1.

Figures 3 and 4 are respective views of the parts of the adjustable connection.

Similar reference characters designate corresponding parts throughout the several figures of the drawing.

The shoe tree embodying the present invention includes the heel section A and the toe section B, the same being adjustably connected by the fastening unit designated generally as C.

The heel section A is provided with the guideway 1 extending longitudinally thereof and is cut away as indicated at 2 to provide a recess or chamber for accommodating a part of the adjustment means and permitting convenient access thereto. The toe section B is formed with a longitudinal slot 3 opening at the top thereof and is also provided at its underside with a ventilating chamber 4 whose upper wall 5 is provided with a plurality of ventilating openings 6—6 and a single relatively large ventilating opening 7.

The adjustable fastening unit C includes in its organization an arm 8 provided with a pivot receiving opening 9 and a longitudinal slot 10 while one edge thereof is provided

with a plurality of keeper teeth 11. The said arm 8 may be fitted to the toe member B by placing the end thereof having the opening 9 in the slot 3 and inserting a pin 9a transversely of the body of the toe section thereby to pivotally lock the arm therein. The rear end 8a of the arm is adapted to be slidably mounted in the guideway 1 so that the arm 8 thereby serves to properly align the sections A and B.

The fastening C also includes a latch member designated generally as 12 and provided at one side with a finger engaging ear 13 while the opposite side is provided with a reduced spring centering portion or port 14. The edge of the body of the latch between the parts 13 and 14 is provided with an offset keeper tongue 15 and the portion of the body opposite the tongue is provided with an opening 16 for receiving a pivot pin 17. This pin is inserted in the heel section through the slot 10 so that the pin 17 thereby becomes the means for fastening the two sections of the device together while at the same time limiting the maximum relative movement thereof.

The heel section A is provided at the bottom of the recess 2 with a spring socket 18 adapted to receive a coil spring 19 whose upper end receives the centering port 14 of the latch 12.

When the parts are assembled, as shown in Figure 2, it will be apparent that the spring 18 normally urges the latch 12 upwardly so that the keeper tongue 15 will engage the teeth 11 of the arm 8. Also, when the sections A and B are in contact the pin 17 will be located at the forward end of the slot 10. When it is desired to adjust one section with reference to the other it is only necessary to depress the latch 12 by exerting finger pressure at the ear 13, thereby to compress the spring 18 and disengage the keeper tongue 15 from the teeth 11. The sections may be then moved the desired distance away from each other and upon release of finger pressure the latch will become interlocked with the arm and thereby hold the sections in their correctly adjusted position.

The arm 8 is one of the distinctive features of the invention since it not only pivotally

connects the two sections so that one may swing with reference to the other for the purpose of fitting them in the shoe, but at the same time the arm keeps the two sections alined in their sliding or adjusting movement, and also with the aid of the pivot pin 17 for the latch and the slot 10, keeps the two sections from coming apart. For maintaining the sections A and B in proper alinement, an abutment 20 may be placed across the slot 3 so that the bottom edge of the arm 8 will rest thereagainst, as shown in Figure 4.

Without further description it is thought that the features and advantages of the invention will be readily apparent to those skilled in the art, and it will of course be understood that changes in the form, proportion and minor details of construction may be resorted to, without departing from the spirit of the invention and scope of the appended claims.

I claim:

1. A shoe tree including heel and toe sections, said sections respectively having a guideway and a slot, an arm pivotally connected to the section having the slot and also having its end opposite the pivotal connection adapted to slide in said guideway, said arm being provided with a slot and having teeth at one edge thereof, a latch having a finger engaging ear and a spring centering post, a spring fitted in a socket in the heel member and adapted to normally urge said latch into locking relation with the teeth of the arm, and a pivot pin for connecting the latch to the heel section through the slot in the arm.
2. In a shoe tree including sections respectively provided with a slot and a guideway, an arm pivotally connected to the section having the slot and the forward end of said arm being slideable in said guideway of the other section, said arm having a slot in the intermediate portion thereof and keeper teeth in the edge thereof below the slot, a spring pressed latch mounted on a pin carried by the section having the guideway, said pin riding in the slot in the arm, a tongue on the latch, and a spring for moving the latch whereby the tongue will engage with the teeth of the arm.
3. A shoe tree comprising heel and toe sections, said heel section having a laterally open recess and a rearwardly extending guideway, and said toe section having a slot opening through the top thereof, an arm consisting of a flat strip pivoted in said slot, and also adapted to enter the guideway of the heel section, teeth formed in the lower edge of the arm and said arm having a slot therein above the teeth, a latch pivoted to the heel section and having its pivot lying in the slot of the arm, said latch also being located in the said recess of the heel section, a tongue on the latch for engaging the teeth on the arm, and a

spring for urging the latch in a direction whereby the tongue will engage with said teeth.

In testimony whereof I hereunto affix my signature.

CHARLES A. BATCHELDER.
